SHUTTLE.

1,079,473.

Specification of Letters Patent.

Patented Nov. 25, 1913.

Application filed February 28, 1912. Serial No. 680,446.

To all whom it may concern:

Be it known that we, JEAN BAPTISTE DAUDELIN and EUSEBE H. DAUDELIN, citizens of the United States, residing at Fall River, county of Bristol, Commonwealth of Massachusetts, have invented certain new and useful Improvements in Shuttles, of which the following is a specification.

Our present invention relates to certain improvements in hand threading shuttles, with particular regard to the checking of any possible escape of a thread from an eye during the run of the shuttle. Heretofore in this art, even the most perfect threading eyes and threading slots have at times failed to hold the thread under the constant writhing and twisting which occurs in the unspooling of the thread from the bobbin.

It is, therefore, the object of our present invention to provide a simple means for preventing the escape of the thread from an eye by which any thread securing device may be rendered more effective and which also makes it possible to construct thread guards and threading eyes with less minuteness of detail and less care, thus reducing the cost of production.

Our invention consists, broadly, in the introduction of a member composed of material in which flexible members are presented with their free ends projecting inwardly toward the threading eye and across the path of entry to that eye so that while a thread may crowd by it in entering it will become entangled with the free ends in any attempt to return.

As illustrative of our invention, we have shown in the accompanying drawings a form of device which we find well adapted to practical use. This form we shall describe as disclosing the principles of our invention and its adaptation to shuttles.

Throughout specification and drawings like reference numerals are employed to indicate corresponding parts and in the drawings, Figure 1 is a plan view of the delivery end of a shuttle embodying our invention, Fig. 2 is a side view of the same, Fig. 3 is a section on the line 3-3, Fig. 2, Fig. 4 a detail of a threading eye plate removed, Fig. 5 is a plan view of a shuttle fitted with another form of eye plate, and Fig. 6 a side view of a shuttle end shown in Fig. 5.

The shuttle body indicated at 1 has the usual chamber in which the bobbin 3 is lo-

cated from which the thread 2 is to be drawn. In the form shown in Figs. 1 and 2 we provide a plate 4 having a pronged inner end and an outer end formed as a depending and rearwardly faced hook 13, the point 10 of which is upturned and carried until it overlaps the edge of the plate. This hook defines the delivery eye 11. The upper surface of the plate is cleared away at 4² for the free passage of the thread and is provided with a forward extension 14 past which the threading slot 6 passes before making its backward turn into the threading eye.

In the modified form shown in Figs. 5 and 6 we have substituted for the hook 13 a pair of curved fingers 10¹ which approach each other closely but leave a narrow opening through which the thread may rise.

Referring again to Figs. 1 and 2, we provide a fibrous member 9, preferably of cotton or hemp, which is rolled in the form of a cord and drawn in through a vertical hole formed through the upper face of the shuttle. The lower end of the fibrous body 80 is allowed to project as a brush between the point 10 and the opposing shoulder of the hook 13. When, therefore, the thread is drawn down through the slot 6 and rearwardly through hook 13 it will pass over 85 the end of the hook into the eye 11, pushing aside the brush-like end of the member 9. Upon attempting to return, however, it will engage the fibers of the brush-like end of the member 9 and become engaged therewith, spreading the same so that escape past the point 10 will be impossible.

In the form shown in Figs. 5 and 6, we have provided a similar fibrous element 9¹. This we have drawn through from the lower 95 side of the shuttle, allowing its free end to project between the points 10¹. In threading the shuttle shown in Figs. 5 and 6 the thread 2 is drawn down through the vertical slot 6 in the same way as last described, 100 then rearwardly until it rises between the points 10¹, 10¹ and into the space 11¹ defined by these fingers. In entering the space 11¹ it passes the end of the brush 9¹ in the same way as described in connection with Figs. 1 and 2. In the same manner, if it attempts to escape the thread will come in contact with the brush-like end of the member 9¹ and become entangled therewith.

It will be readily apparent to those skilled 110

in the art that our invention may be applied in combination with a great variety of forms of threading eyes and thread guards.

- 5 Our fibrous member may be in the form of a cylindrical brush or as an elongated strip according to the nature of the passage which it is intended to close. We do not, therefore, limit our invention to any 10 particular form of member or to any particular material, all such modifications being understood to be within the scope of our invention if within the limits of the appended claims.
- 15 What we therefore claim and desire to secure by Letters Patent is:
1. In a shuttle having a threading eye and a threading slot, a guard fitted in said eye and having a pair of points defining said eye but with a passage between their ends, and a fibrous member projecting between said points and having free fiber ends disposed inwardly therebetween.
  2. In a shuttle of the class described having a threading eye and a threading pas-

sage leading into said eye, a thread check composed of longitudinally disposed fibers set in said passage and disposed inwardly along said passage toward said eye and having no exposed fiber ends at its outer part, 30 but having a surface of free fiber ends projecting toward said eye and effectively blocking said passage to prevent backward movement of a thread through said passage.

3. In a shuttle having a threading eye and a threading slot leading into said eye, a thread check composed of longitudinally disposed fibers set in said passage and having its free fiber ends disposed inwardly toward said eye and exposed in said eye 40 through the entry of the threading slot therein.

In testimony whereof we affix our signatures in presence of two witnesses.

JEAN BAPTISTE DAUDELIN.
EUSEBE H. DAUDELIN.
